UNITED STATES PATENT OFFICE.

WILBUR N. MAYNARD, OF LEOMINSTER, MASSACHUSETTS.

HANDLE.

SPECIFICATION forming part of Letters Patent No. 700,354, dated May 20, 1902.

Application filed March 3, 1902. Serial No. 96,445. (No model.)

To all whom it may concern:

Be it known that I, WILBUR N. MAYNARD, a citizen of the United States, residing at Leominster, in the county of Worcester and State of Massachusetts, have invented certain new and useful Improvements in Handles; and I do declare the following to be a full, clear, and exact description of the invention, such as will enable others skilled in the art to which it appertains to make and use the same.

The invention relates to handles, and more particularly to that class intended for use on the valve chain or cord of a water-tank.

The object of the invention is to provide a handle of this character which shall be simple of construction, durable in use, comparatively inexpensive of production, and which may be easily and quickly connected to the valve chain or cord.

With this and other objects in view the invention consists of certain novel features of construction, combination, and arrangement of parts, which will be hereinafter more fully described, and particularly pointed out in the appended claims.

In the accompanying drawings, Figure 1 is a longitudinal sectional view of one form of my invention, showing a grip consisting of two parts. Figs. 2, 3, and 4 are similar views illustrating other forms of my invention.

The handle or grip consists of the sections 1 and 2, the former of which is hollow and provided with a contracted neck 3. The section 2 of the handle is provided with a plug 4, which enters the section 1 between the shoulders 5 and 6 of the sections 1 and 2, and around the plug is adapted to be clamped an annular buffer 7 in the form of a rubber ring. 8 denotes the valve chain or cord, and 9 denotes a spring for fastening the valve chain or cord to the handle. This spring extends entirely through the handle and has its outer end formed with a head 10, which is of such size as to prevent it from being drawn through the bore 11 of the section 2 of the handle.

The end of this bore may be countersunk, as shown at 12, and a metal ferrule or seat 13 inserted to form a neat finish and to contract that end of the bore 11, and thus prevent the withdrawal of the head through said bore. The opposite end of the spring is doubled upon itself to form a frictional arm 14, which

tends to spread away from the body or straight portion of the spring, and thus exerts a frictional energy upon the inner wall of the part 1, 55 and thus serves to prevent the separation of the parts 1 and 2 and also to prevent the spring and chain from working downwardly through the lower end of the handle when said handle is raised. The outer end of the part 1 may, if desired, be furnished with a ferrule 15 to add to the general finish of the handle.

In the construction shown in Fig. 2 the handle is represented as consisting of one piece. 65 The spring is similar in construction to that shown in Fig. 1 and so also is the ferrule for restricting the bore through the handle, and thus preventing the withdrawal of the head through said bore.

In the construction shown in Fig. 3 instead of providing the spring with a head and a ferrule to prevent the withdrawal of the head through the handle I provide a plug *a*, with a hook *b* to engage the arm of the spring, and thus prevent the withdrawal of the spring 75 through the handle.

In the construction shown in Fig. 4 I have shown the lower end of the spring secured to a plug fitted in the lower end of the handle, 80 while the upper end of the spring is provided with a bow *d*, which terminates in a spring-arm *e*, and to this bow is adapted to be attached the valve cord or chain. The plug will prevent the withdrawal of the spring 85 through the handle, and the bow will prevent the spring and chain working downwardly through the bore of the handle.

From the foregoing description, taken in connection with the accompanying drawings, 90 the construction, mode of operation, and advantages of my invention will be readily understood without requiring an extended explanation.

Various changes in the form, proportion, 95 and details of construction may be made within the scope of the invention without departing from the spirit or sacrificing any of the advantages thereof.

Having thus described my invention, what I claim, and desire to secure by Letters Patent, is—

1. A handle for the purpose described having a bore extending therethrough, a spring

located within said handle and adapted to be connected to the valve chain or cord, means for positively preventing the withdrawal of the spring from the handle in one direction, 5 said spring exerting its energy to prevent its movement through the handle in the opposite direction, substantially as set forth.

2. A hollow handle for the purpose described, a spring located within the hollow 10 handle and provided at one end with a spring-arm adapted to bear against the interior wall of the handle and limit the movement of the spring in one direction and afford means for the connection of the valve cord or chain, said

spring being provided at its outer end with a 15 head to limit the movement of the spring in the opposite direction and thereby prevent the withdrawal of said spring through said handle when the handle is grasped and pulled down, substantially as set forth. 20

In testimony whereof I have hereunto set my hand in presence of two subscribing witnesses.

WILBUR N. MAYNARD.
